DESIGN FOR A COMBINATION LAUNDRY- TRAY COVER AND DRAIN-BOARD

Albert H. Gross, Oakland, Calif.

Application February 24, 1934, Serial No. 50,842

Term of patent 3½ years

To all whom it may concern:

Be it known that I, Albert H. Gross, a citizen of the United States and a resident of the city of Oakland, county of Alameda, State of California, have invented a new, original, and ornamental Design for a Combination Laundry-Tray Cover and Drain-Board of which the following is a specification, reference being had to the accompanying drawing, forming part thereof.

I claim:

The ornamental design for a combination laundry-tray cover and drain-board substantially as shown.

ALBERT H. GROSS.
